[57] **CLAIM**

The ornamental design for galley retainer, as shown and described.

DESCRIPTION

FIG. 1 is a perspective view of the galley retainer showing the new design;

FIG. 2 is a top elevational view of the embodiment of FIG. 1;

FIG. 3 is a left side elevational view of the embodiment of FIG. 1;

FIG. 4 is a bottom elevational view of the embodiment of FIG. 1;

FIG. 5 is a right side elevational view of the embodiment of FIG. 1;

FIG. 6 is a front elevational view of the embodiment of FIG. 1;

FIG. 7 is a back elevational view of the embodiment of FIG. 1;

FIG. 8 is a perspective view of an alternative embodiment of the galley retainer of FIG. 1;

FIG. 9 is a top elevational view of the embodiment of FIG. 8;

FIG. 10 is a left side elevational view of the embodiment of FIG. 8;

FIG. 11 is a bottom elevational view of the embodiment of FIG. 8;

FIG. 12 is a right side elevational view of the embodiment of FIG. 8;

FIG. 13 is a front elevational view of the embodiment of FIG. 8; and,

FIG. 14 is a back elevational view of the embodiment of FIG. 8.

The broken line showing of a bolt is for illustrative purposes only and forms no part of the claimed design.
